UNITED STATES PATENT OFFICE.

GEORGE P. FENNER, OF NEW LONDON, CONNECTICUT.

SHEET-DELIVERY APPARATUS.

SPECIFICATION forming part of Letters Patent No. 692,840, dated February 11, 1902.

Application filed May 16, 1901. Serial No. 60,535. (No model.)

To all whom it may concern:

Be it known that I, GEORGE P. FENNER, a citizen of the United States, residing at New London, in the county of New London and 5 State of Connecticut, have invented new and useful Improvements in Sheet-Delivery Apparatus, of which the following is a specification.

By means of this invention sheets coming 10 from a printing-press can be suitably delivered with the face or printed side down, if desired; and the invention resides in certain novel features of construction set forth in the following specification and claimed, and illustrated in the annexed drawings, in which—

Figure 1 is a side elevation of a sheet-delivery apparatus. Fig. 2 is a plan view of Fig. 1. Fig. 3 shows a detail from the side opposite to that exposed in Fig. 1. Fig. 4 20 shows a modification.

In the construction shown sheets coming 25 from a press or impression-cylinder are carried along between two aprons. The term "apron," it is manifest, includes any equivalent—such as tapes, or ribbons, or sheet-carriers—known in the art. The impression-cylinder is indicated at *a* and aprons at *b*. From the apron pair *b* the sheet passes to sheet-delivery apron or tapes *c*, having an 30 end or edge fixed or secured to an immovable bar or cross-piece *d*. A reciprocating roller is shown at *e* and is adapted to wind the apron. The roller *e* is rotated in one direction by a spring after the manner of a well-known class of window-shade roller, so as to continually tend to keep the apron *c* taut and to cause said apron to be wound about the roller when the latter moves toward the fixing-point *d* of the apron or the point at which 35 the fixed end of the apron is secured. The movable end of the apron being secured to roller *e*, such apron is wound about the roller as the latter travels back or toward cylinder *a*. A delivery-roller *f* travels with or is 40 mounted on the reciprocating carriage of roller *e*. It should be noted that the rollers *e* *f* are not actually in contact with one another. A sheet from apron *c*, carried between delivery-roller *f* and pressure roller or disks 45 *g*, will be bent or turned by the reverser or curler *h*, so as to be reversed or land printed side down on the receiving-board. The re-

verser or curler is formed by a set of bent or concave fingers, which are mounted or fixed to a shaft or cross-bar extended across the carriage *m* or mounted on the side pieces or bracket *n*.

The roller *f* is rotated in one direction by ratchet and pawl *i* *h*, Fig. 3. The pawl *h* is carried by gear *l*, geared to roll *e*, which winds up the apron *c*. The parts *f* *g* *h* can be suitably mounted on or form part of a bracket *n*, and by dismounting the bracket off the carriage the reversing of the sheet is dispensed with. The reversing device can thus be applied or not, as called for.

Say the roller *e* is near the fixed point *d* and starts forward or away from such piece *d*. The roller *f* travels not only with said roller *e*, but in addition is rotated by the gear *l*, driven by roller *e*, so that the sheet whose leading edge has been taken between such delivery-roller is moved with increased speed, so as to slide off the apron *c* and fall on its face or printed side on the receiving-board—that is to say, before the delivery-roller has taken hold of the sheet or so long as the latter is only fed by apron *b* such sheet will travel at the speed of such apron, but after the delivery-roller has taken hold of the sheet the latter is drawn off the apron by the increased speed imparted to the sheet by such roller.

The device can be modified. The curler or reversing portion *h*, instead of being in the form of a rigid plate or fingers, can be formed of an apron or tapes, Fig. 4. Guide-rollers *o* can cause the reversing-tape to clasp or suitably extend about the delivery-roller *f*. It has also been noticed that the presser-roller *g*, if made to contact with the upper part of the presser-roller *f* at a point forward of the axis of such roller, will cause the sheet to bend or slightly deflect downward as it passes from the roller *f*. Such downward bending of the leading edge of the sheet, combined with the weight of the sheet and the resistance of the air as it passes from the forwardly-moving roller *f*, tends to cause such sheet to reverse or land on its face, even without the application of curlers *h*. The dispensing with curlers or reversers is, however, not deemed advisable unless the machine runs at comparatively low or moderate speed.

The ratchet and pawl on roller *f* are not essential, but serve to relieve the spring on roller *e*, as the rotary motion of this roller is produced in one direction by a spiral spring, which is wound up. After the sheet is delivered it is immaterial in which direction roller *f* rotates.

The carriage of roller *e* can be suitably reciprocated or driven, as by rack *m*, (shown as forming a side of the carriage.)

What I claim as new, and desire to secure by Letters Patent, is—

1. A sheet-delivery apron, a roller for winding and unwinding said apron, means for effecting the reciprocation of said roller, means for holding a part of the apron against reciprocation with said roller, a delivery-roller arranged to travel with and to receive a sheet from said first-mentioned roller, and a sheet-reverser arranged to coact with said delivery-roller.

2. A sheet-delivery apron having a fixed end, a reciprocating roller about which said apron is wound, and a delivery-roller and reversing-guide made to reciprocate with the first-named roller, a ratchet and pawl for rotating the delivery-roller, and an actuating-gear for the ratchet and pawl.

3. An impression-cylinder, a sheet-delivery apron having a fixed and a movable end, a reciprocating roller for the movable end, a de-

livery-roller made to travel with the reciprocating roller, a ratchet-pawl and gear for actuating the delivery-roller when traveling away from the impression-cylinder, and a second gear carried by the reciprocating roller and made to engage the ratchet-pawl gear.

4. A sheet-delivery apron, a roller for winding and unwinding said apron, means for effecting the reciprocation of said roller, means for holding a part of the apron against reciprocation with said roller, a delivery-roller arranged to travel with and to receive a sheet from said first-mentioned roller, and a sheet-reverser having a concaved face arranged contiguous to the periphery of said delivery-roller.

5. A sheet-delivery apron, a reciprocating roller for winding and unwinding one end of the apron, a delivery-roller made to reciprocate with the first-named roller, a reversing tape or tapes extended about the delivery-roller, and guide-rollers for the tape extended about the delivery-roller.

In testimony whereof I have hereunto set my hand in the presence of two subscribing witnesses.

GEORGE P. FENNER.
